UNITED STATES PATENT OFFICE.

FREDERICK EGGE, OF BRIDGEPORT, CONNECTICUT, ASSIGNOR TO THE SMITH & EGGE MANUFACTURING COMPANY, OF SAME PLACE.

BUTTON-HOLE SEWING-MACHINE.

SPECIFICATION forming part of Letters Patent No. 298,957, dated May 20, 1884.

Application filed July 1, 1882. (Model.)

To all whom it may concern:

Be it known that I, FREDERICK EGGE, a citizen of the United States, residing at Bridgeport, in the county of Fairfield and State of Connecticut, have invented certain new and useful Improvements in Button-Hole Attachments for Sewing-Machines; and I do hereby declare the following to be a full, clear, and exact description of the invention, such as will enable others skilled in the art to which it appertains to make and use the same.

My invention relates to certain new and useful improvements in button-hole sewing-machines, which may be best understood by reference to the accompanying drawings, which illustrate my machine in combination with an ordinary Wheeler & Wilson sewing-machine.

Figure 1 is a vertical section of my improved machine, taken through the line $z z$, Fig. 3; Fig. 2, a top view of the same with the standard and needle-bar of the sewing-machine cut away; Fig. 3, a bottom view of my machine as applied to a sewing-machine, with the driving-wheel in section; Fig. 4, a section at line $x^3 x^3$, Fig. 2; Fig. 5, a top view between the lines $x^4 x^4$ and $x^5 x^5$ with the presser-foot removed; Fig. 6, a section at line x^6 , Fig. 5; Fig. 7, a section at line x^7 , Fig. 2. Fig. 8 is a plan or top view of what will hereinafter be referred to as the "tray." Fig. 9 is a detail view of what will be designated as the "clutch-vise." Figs. 10, 11, and 12 are detail views of parts carried by the tray shown in plan at Fig. 8. Fig. 13 is a vertical section at line x^4 of Fig. 7. Fig. 14 is a horizontal section taken at line $x x$ of Fig. 1. Fig. 15 is a detail view of driving-wheel, showing the stud for locking with the sliding feather on its shaft. Fig. 16 is a plan view of the switch-cam and traveler; Fig. 17, a perspective view of the drive-bar. Fig. 18 is a perspective view of the carrier and feed-bar in operative position. Fig. 19 is a perspective view of the tray. Fig. 20 is a perspective of the tray with the cap on, and showing more particularly the three-toothed wheel and the spring-dogs shown in detail at Figs. 10 and 12 in their relative positions; Fig. 21, a detail view of what will be hereinafter designated as the "vibrating pocket," and Fig. 22 a

perspective view of the mechanism used to connect my machine with the motive power.

My invention is designed especially to render the operation of stitching and barring the button-hole automatic in every particular and to do away with pawls and ratchets in connection with the feed mechanism; and with these objects in view my invention consists in the novel organization of parts and in certain combinations of devices hereinafter fully described and specifically claimed.

A is the case, made of cast-iron or any suitable material, having an opening, B, into which fits a pin, C, arranged on the drive-bar D'. This drive-bar is caused to operate by means of a pin, E, which fits into a traveler, F, in the switch-cam G² on the shaft of the machine. The pin C, in its movement, comes in contact with a tray, D², (shown in section at Fig. 13 and in perspective at Fig. 20,) which slides in V-shaped grooves a. This tray is composed of a flat plate, through which runs a spindle, G, Fig. 12, provided with a disk, b, with beveled trip c projecting from its periphery. This spindle terminates in a disk, d, having also a trip, e, beveled on the under side. The plate is confined between the two disks, and over the upper disk is a standard, H, to which are pivoted on each side spring-dogs f, having beveled teeth g, Figs. 7, 8, 10, and 19. The standard H rests upon the tray D², and the disk b is free to revolve and operate on the dog f, as will be hereinafter explained, the arrangement of the spindle, standard, and tray being such that the sliding of the latter will carry with it the said spindle and standard. The pin C on the drive-bar D' (see Fig. 13) is shown between said dogs f, so that it will be readily understood that any longitudinal movement of said drive-bar will cause the tray D² to slide accordingly, since the standard H, to which the dogs f are attached, is secured to the spindle G, which also passes through the said tray. If one of the dogs be lifted so that the pin will be free to move underneath the same, then of course the length of the slide (in the direction of the upraised dog) imparted to the tray D² will be lessened by the width of said dog. Except when the machine is performing the function of barring, one of these dogs is always 100

raised by means of the trip *c* coming in contact with the tooth *g* of the dog *f*, as will be more readily seen at Figs. 19 and 20, and the object of this and the relation existing between 5 the drive-bar and tray will be hereinafter more fully and in detail explained. The tray *D*² is provided with a pin, *I*, secured by nut and rivet, Figs. 2, 13, and 14, which travels in a deflected or inclined slot, *A*², in a jog-link, 10 *D*³, (see Fig. 14,) the arrangement of this slot being such that as the tray slides the pin *I* will act on the jog-link and give it a motion in a plane at right angles to that of the previously-mentioned drive-bar and tray. This jog-link 15 *D*³ is provided with a gating, *K*, into which is fitted and pivotally attached, by means of the screw *h*, one end of the oscillator *L*, so that it will be readily understood that any movement of the jog-link *D*³ will affect the oscillator, 20 but in what particular manner and for what purpose I will presently explain. This oscillator *L* passes through an independent vibrating pocket, *M*, (shown in detail at Fig. 21,) which consists of a circular piece of metal, 25 provided with a gating, *N*, and fitting into a recess in a slide, *O*.

P is a set-screw, by means of which the slide can be fastened at any desired point. By 30 means of the slide *O* the distance between it and that part of the oscillator *L* pivoted by the screw *h* is increased or lessened, thereby giving to the oscillator a less or greater vibration at its further extremity, for the purpose of causing a narrower or wider stitch of the 35 button-hole, in the manner and for the purpose hereinafter more fully explained.

Directly upon the oscillator *L* is placed the feed-bar *Q*, provided at one end with a hook-arm, *R*, and having two bearings, *i j*, the latter of which is threaded. Through these bearings passes a shaft, *S*, threaded to serve as a screw in the bearing *j*, and operated by a thumb-wheel, *k*. The upper end of this feed-bar is provided with a pin, *l*, Fig. 1, which projects from the under side of the bar, and which is designed to fit into a hole in a step, *m*, on a slide, *T*, which travels in a groove in the fore part of the oscillator. The objects attained in thus practically making the feed-bar in two 50 sections is the great convenience in the manufacture and also in assembling the several parts. To the forward and detachable end of this feed-bar is attached, in any suitable manner, any ordinary presser-foot, *U*, of form and style advantageous to the manufacture of button-holes, and operated by the usual cam-lever. Upon the feed-bar *Q* and pivotally attached to the case *A* is a clutch-vise, *V*. (Shown in operative position at Fig. 5 and, in detail 55 at Fig. 9.) This vise is made with jaws *n o*, the latter pivoted by a screw, *p*, to the vise-bar, and the former bearing against a spring, *q*, confined by a pin, *r*, and operated by a dog, *s*, pivoted by a screw, *t*, to the vise-bar. This 60 dog is beveled at the heel end in contact with the vise, so that any rocking or vibration of said dog will cause the latter to act like a cam

against the jaw *n*, and thereby cause the jaws to grasp the feed-bar *Q*. The function of the spring *q* is to give a spring action to the jaw 70 *n* and to throw the jaws out of engagement with the feed-bar when the dog *s* is not acting on said jaw *n*.

W is a flat spring secured to the case *A* and bearing against the clutch-vise *V*, the object 75 of which is to give a spring movement to the vibrations of the vise, as will be presently explained.

X is a short metal spring bearing upon the feed-bar *Q*, in order to prevent the said feed-bar from slipping, and also to steady the movement of the same.

Y is a plate which is secured to the case, and having pivotally attached thereto two dogs, *u v*.

Attached to the tray *D*² in such a manner as to permit free vibration is a lever, *A'*, provided with a single tooth, *w*, and adjusted by means of a screw, *a'*, in the side of the case, the relations of which to the dogs *u v* and the clutch-vise *V* can be more readily comprehended by reference to Fig. 5 of the drawings. As the tray *D*² moves forward, the tooth *w* is forced against the dog *v*, thereby crowding it in turn against the side 1 of the dog *s*, which, 95 as hereinbefore explained, operates the vise and causes it to grasp the feed-bar *Q*, and, furthermore, by reason of the inclination of said side 1 of the dog *s*, the action of the dog *v* thereon also causes the vise to move forward 100 until the tooth *w* has passed the dog *v* and ceased to crowd the same. The vise immediately releases the feed-bar, owing to the normal repose of the dog *s*, and by reason of the spring *W* drops back to its original position. Thus it will be 105 seen that by moving the tooth *w* from the position shown in Fig. 2 to that shown in Fig. 5 the feed-bar has been advanced, and it is clear that by a reverse movement the dog *v* will operate on the dog *s* in precisely the same way 110 and with the same result. Therefore I will state at this point that the forward movement of the feed-bar *Q* is effected by the action of the dog *v* on the dog *s*, and as the functions and relations existing between the dog *u* and 115 the side 2 of the dog *s* do not differ in the least from those already explained relative to the dog *v*, it follows that, the pressure in this latter case being upon the side 2 of the dog *s*, the backward movement of the feed-bar is 120 effected by the action of the dog *u* on the dog *s*. The intervals in the movement of the feed-bar depend entirely on the amount of pressure brought to bear upon the inclined surfaces 1 and 2 of the vise, and this is rendered greater 125 or less, according to the adjustment of the lever *A'*, by means of the screw *a'*.

B' is a catch-lock device, by means of which motion is transmitted to the attachment, (see Fig. 22,) and consists of a piece of metal of 130 suitable shape, terminating in or provided with a pin or trigger, *C*, at one end, and having a catch-tooth, *b'*, (see Fig. 22,) at the lower portion.

- D is a flat spring, secured at one end to the bed-plate by a screw, and with the other end fitting into the slot e' , so that the device B' has a spring movement vertically.
- 5 E' is a rod or arm, one end of which passes through the bed-plate, and is secured by nuts d' , and the other end extends through the opposite side of the bed-plate, and is connected with a knob or button, F', Fig. 2, by any suitable arm, G'. This rod E' passes through an opening in the device B', and is curved near its center for the purpose presently explained.
- H' is the shaft, which has an elongated slot, e' , in which plays a slide, I', which moves, in conjunction with a sliding collar, J', by means of a screw, which extends through the latter into a depression or recess in the former, as clearly shown at Fig. 1.
- 15 K' is a spring arranged between the collar J' and the cam L', so that the former has a spring movement. Thus it will be understood that when the arm E' is moved past the tooth b' in the device B' it will act on the collar J', thereby moving the end of the slide I' into a recess, g' , in the driving-wheel M'. In this recess there is fastened in any suitable manner a lug, h' , Figs. 1 and 3, which engages with the end of the slide I', thereby giving motion 25 to the shaft H' as the driving-wheel M' revolves. The arm E' is bent or curved near its center, so that there shall be no lost motion between it and the collar J', while at the same time, the movement of the curved or bellied portion being faster than that of the part engaging with the tooth b' , by a well-known mechanical principle, it follows that the slide I' will be forced a correspondingly greater distance into the recess g' , which is a result to be 35 aimed at, since it increases the hold of the slide by presenting more surface to be acted upon by the lug h' . When the knob F' is operated, the arm E' is being moved against the bevel of the tooth b' , and causes a movement 40 of the device B' opposite to the action of the spring D, and it is clear that as soon as the arm has passed the tooth the spring will cause the device to drop back to its original position, and thereby lock the arm against retraction. This device B' terminates in or is provided with a spindle or trigger, C', as hereinbefore set forth, which is beveled on its end in any desired manner. This trigger extends 45 upward through the bed-plate and through the case A within the field of movement of the trip e', (see Fig. 18,) so that when said trip comes in contact with the trigger the nature of their bevels will cause the trigger to be pressed downward, and thus release the arm E', for the purpose hereinafter fully explained.
- 50 Thus it will be observed that the movement of the arm E' is the prime auxiliary to the application of the motive power to the attachment proper, while at the same time the depression of the trigger C' when the attachment is in 55 operation will cause the action of the same to be immediately suspended by reason of the withdrawal of the slide or arm I' from contact with the lug h' .
- In the spindle G, Figs. 12 and 18, is a pin, i' , which projects on each side so as to afford a grasp or foot-hold for a toothed wheel, N', which is placed in position over the spindle, as shown at Figs. 2 and 20, so that any rotation of the wheel would cause a similar rotation of the spindle and the parts attached thereto.
- O' is a cap, which is placed over the standard H, said cap having an elongated opening through which the spindle G projects, Fig. 20. Attached to this cap are two pawls, j' , whose movement is of a spring character by reason of springs k' at their rear ends. When the feed-bar Q is moved forward by the action of the vise V, its hook end R comes in contact with the trip e, Fig. 18, and carries the same along with it until the wheel N' has been rotated sufficiently far so that the first tooth thereof, which I have designated by the letter z' , strikes the pawl j' , as seen at Fig. 20, during the sliding movement of said wheel through the cap O'. This causes the wheel to revolve, and the action of said pawl on said tooth brings the teeth z^2 and z^3 successively within the field or reach of the pawl, so that they are 90 similarly rotated. The trip e has been thus carried around to the position as seen by dotted lines, Fig. 18, and, as will be presently explained in detail, the motion of the feed-bar is now reversed, and the arm S acts on the trip e in precisely the same manner as the hook end R, and the contact of the teeth with the other pawl, j' , opposite to that above mentioned, operates to revolve the wheel N', as previously set forth, and that after the third tooth, z^3 , has been turned by the pawl, the trip e, in its rotation, comes in contact with the trigger C' and stops the motion of the attachment, as hereinbefore set forth. In order to 95 more clearly illustrate my improvement, I will proceed to describe the operation of the same and the peculiarities and application of the various parts, as best seen from a practical stand-point.
- The machine is set in motion by the lug h' 115 coming in contact with the slide I', which slide is operated by moving the knob or button F' by hand toward the driving-wheel, the details of which operation and the construction of the several parts having been already fully explained. As the shaft revolves the action of the traveler F in the switch-cam G² causes the drive-bar D' to move in a line parallel to the shaft, and at the same time, by reason of the connection with the tray D², it causes the latter to move in a similar direction. As the pin I, attached to the tray D², moves forward or backward with the movement of the tray, said pin travels in a slot, A², in the jog-link D³. This slot is deflected from the line of movement of the pin, and the jog-link being free to move laterally, it follows that the action of the pin within the deflected slot will give a lateral reciprocating motion to said jog-link, or, in 120
- 130

other words, a motion at right angles to that of the previously mentioned drive-bar and tray, whereby the oscillator L, connected to said jog-link, is vibrated for the obvious purpose of shifting the cloth or other material underneath the needle.

In order to perform its functions properly and uniformly, the machine at its initial movement is in about the position shown at Fig. 19. 10 By reference to this figure it will be seen that the trip e is in a position under the tooth g of the pivoted dog f, so that the latter is raised, and the pin C, Fig. 13, in its movement forward, will pass underneath the dog f without 15 coming in contact with it. This of course shortens the slide of the tray D² by a distance equal to the width of the raised dog, so that as long as the position of the trip e and dog f is as shown at Fig. 19 the lever A', Figs. 2 20 and 5, will move to and fro only about half of its sliding limit, and the tooth w will consequently operate on the rear dog, v, thereby causing the feed-bar Q to move forward during both the forward and backward slide of 25 the tray D², as hereinbefore set forth. During the process of this operation, while the feed-bar is constantly advancing, the hook R comes in contact with the trip e, Fig. 18, and forces it along with it until it has carried the trip e 30 from under the tooth g, when the dog f drops, and the position of the pin C being now immediately between the two dogs f, there will be no lost motion, but the tray D² will slide to its full extent, causing the lever A' to operate 35 through the medium of its tooth w upon both of the dogs u v, thereby effecting a neutralization of the feed movements, so that the bar Q will move forward and backward at each slide of the tray D², while at the same time, the tooth 40 z' of the wheel N' having been brought into a position so as to strike the recess in the pawl j', each backward slide of the said tray will cause the rotation of the wheel in the manner hereinbefore set forth until it has carried the 45 trip e around underneath the tooth of the rear pivoted dog, f, at which time the tray D² has advanced to its fullest extent, so that, as before, said slide will move only one-half of its limit; but in this latter case the tooth w will 50 operate on the forward dog, u, thereby causing the backward movement of the feed-bar Q, as hereinbefore set forth.

It will be readily understood by reference to Fig. 18 that, the trip e having been carried 55 around by the revolution of the wheel N' to the position as indicated in dotted lines, the arm or shaft S, during the backward movement of the feed-bar, will operate precisely as did the hook R during the forward movement, and the functions of the wheel N' and the action of the opposite pawl, j', will be precisely the same, and will have the same result, with the exception that the trip e, during 60 its revolution, strikes the beveled trigger O' and causes the attachment or machine to stop running. This trigger, however, is situated at such a point in the arc of revolution of the

trip e that no necessary movement of the machine is lost, and said trip, at the end of each revolution, has consequently brought the trip 70 e to the position from which it started—viz., underneath the tooth g of the forward pivoted dog, f—so that when the machine is again set in motion the shaft will have the same number of revolutions, and therefore the work of 75 finishing button-holes will be uniform and complete. The feed-bar Q is regulated in its movement by the screw a', Fig. 5, as the dogs u v are thereby caused to crowd the beveled nose of the vise-bar V more or less, thus forcing the latter forward or backward, as the case may be, a greater or shorter distance, for the purpose of varying the distance between the stitches of the button-hole. As hereinbefore explained, the vibration of the oscillator 85 L is regulated by the slide O, upon the adjustment of which depends the width of the stitch. The scope of the vibration of the oscillator is doubled at the barring operation, because the slide of the jog-link D³, to which 90 the oscillator is attached, is twice as great at this time, owing to the increase of the slide of the tray D², as hereinbefore set forth. The length of the button-hole is governed by the action of the feed-bar Q and its arm S, for, if 95 a shorter button-hole be desirable, the operator merely pushes the feed-bar forward until the distance between the needle-hole in the bed-plate of the machine and the rear end of the presser-foot proper is equal to the required 100 length of the button-hole. The hook-arm R will then be in a position to act sooner upon the trip e, and the arm S must likewise be adjusted inward by means of the thumb-wheel k. For the sake of convenience and accuracy, 105 graduated scales may be marked off on the slide T and bar S.

P' is an auxiliary presser-foot, pivoted at l' and operated by the mechanism illustrated at Fig. 6, in which I have shown a wheel, Q', 110 having a piece, m', secured thereon, so that a portion of the periphery of said wheel will be raised in order to operate upon the pivoted arm R', the upper end of which is in contact with a pin, n', on the rear end of the presser-foot P'. A spring, o', bears upon the pin n', as seen at Fig. 14, by reason of which the presser-foot flies back as soon as the raised surface m' has ceased to operate on the pivoted arm R'. This piece m' is so arranged as regards the timing of the machine that it causes the forward end of the presser-foot P' to descend and bind the cloth just before the needle punctures the same, and it remains in this position until the needle has been withdrawn. The 115 object of this is to prevent the cloth from cockling, and thereby distorting the button-hole. I have shown a small slot in the extreme forward end of this presser-foot P', in which a knife or cutter of any desired shape 120 can be placed, so as to cut the button-hole during the process of stitching; but I prefer to cut it in the usual manner after it is made. Should an increased number of barring-stitches be-

come desirable, this can be effected by an additional number of teeth on the wheel N', and at the same time the length of the teeth is shortened, so that the revolution of the wheel 5 will be less at each action of the spring-pawls.

I have shown and described mechanism for limiting the number of oscillations and automatically stopping the machine, and also means for throwing the machine in and out of connection with the driving-wheel; but I do not wish to be understood as claiming herein any such construction, broadly, as I have claimed the latter in my pending application for Letters Patent, No. 98,950, Serial, filed June 22, 15 1883.

Having described my invention, what I claim, and desire to secure by Letters Patent, is—

1. In a button-hole sewing-machine or attachment, the combination of the drive-bar, tray, jog-link, and mechanisms for operating the same, substantially as set forth.

2. The drive-bar D', provided with pins E C, in combination with means for imparting motion to said bar, dogs f, pivoted to the standard H, and tray D², substantially as described.

3. The tray D², having a pin, I, in combination with means for operating said tray, jog-link D³, provided with a diagonal slot, and the oscillator, substantially as shown and described.

4. The standard H, mounted on the tray D², and having pivoted spring-dogs f, in combination with means for raising said dogs, the drive-bar D', having pin C, and mechanism for actuating said bar, substantially as set forth.

5. The spindle G, provided with the pin i', disk b, with beveled trip C, and disk d, with 40 beveled trip e, in combination with toothed wheel N' and means for operating the same, dogs f, feed-bar Q, and push-bar S, and hook-arm R and means for actuating the same, as and for the purpose set forth.

45 6. The spindle G, extending through the standard H, and provided with trips c e, in combination with the dogs f and trigger C', as set forth.

7. The drive-bar D', provided with pins E C, in combination with the switch-cam G², having traveler F, dogs f, pivoted to the standard H, and tray D², substantially as set forth.

8. The jog-link D³, provided with gating K, and diagonal slot A², in combination with the 55 oscillator L, and pin I, secured to the tray D², and means for operating said tray, substantially as set forth.

9. In combination with the jog-link provided with a gating, the oscillator L, and adjustable plate O, as described.

60 10. The vibrating pocket M, arranged in the adjustable slide O, in combination with the oscillator L, jog-link D³, provided with diagonal slot, and tray D², having secured thereto the pin I, substantially as described.

11. The arm A', pivoted to the tray D², in

combination with the pivoted dogs u v and adjusting-screw a', substantially as described.

12. The vise V, provided with jaws n o, and pivoted nose S, in combination with the feed-bar Q, dogs u v, lever A', provided with tooth w and tray D², and means for operating the same, substantially as described. 70

13. The vise V, pivoted at the forward end with spring-acting jaws, as described, in combination with the pivoted nose and means for operating the latter, and the feed-bar, substantially as described. 75

14. The jaw o, pivoted to the vise-bar V, in combination with the spring-jaw n and pivoted nose s, substantially as set forth. 80

15. The combination of the vise-bar provided with spring-jaws with the feed-bar and means for imparting an intermittent action to said jaws, and means for effecting a reciprocating movement of the vise-bar in a horizontal plane, whereby the feed-bar may be grasped by the said jaws and carried forward or backward, substantially as described. 85

16. The pivoted dogs u v, in combination 90 with the nose s, jaws n o, feed-bar Q, and means for operating said dogs, substantially as shown and described.

17. The nose s, pivoted to the forward end of the vise V, and provided with inclined 95 sides 1 2, and with its rear corners beveled, in combination with the jaws n o and means for operating said nose, substantially as set forth.

18. The combination of the arm A' with the 100 dogs u v, vise V, and feed-bar Q, substantially as set forth.

19. The feed-bar Q, with hook-arm R and adjustable arm S, in combination with mechanism for actuating the same, trip e, secured 105 on the lower portion of the spindle G, and wheel N' and means for operating the same, substantially as set forth.

20. The combination of the drive-bar D' and tray D² with the oscillator L, jog-link D³, 110 arm A', pivoted dogs u v, vise V, and feed-bar Q, whereby the forward portion, T, of the latter will have a forward and at the same time an oscillatory motion, as and for the purpose set forth. 115

21. The oscillator L, pivoted at its rear end to the jog-link D³, and provided at its forward end with a groove, in combination with the forward portion, T, of the feed-bar and means for operating said oscillator and feed-bar, substantially as described. 120

22. The oscillator L, pivoted to the jog-link D³, in combination with the vibrating pocket M in the adjustable block O and means for operating said jog-link, substantially as shown 125 and described.

23. The combination of the spindle G, provided with the trips c e, pivoted dogs f f, feed-bar Q, with hook-arm R and adjustable arm S, wheel N', pawls j j, standard H, pin C', and cap O', substantially as set forth. 130

24. The wheel N', provided with teeth, and

recessed as described, in combination with the spindle G, having pin *i*, pawls *j* *j'*, sliding tray D², and mechanism for operating the same, feed-bar Q, with hook-arm R and adjustable arm S, and trip *e*, secured on the lower extremity of said spindle, substantially as set forth.

25. The cap-plate O', with elongated central opening, and provided with spring-pawls *j*', in combination with the spindle G, attached to the tray and carrying the toothed wheel N', mechanism for actuating said tray, feed-bar Q, with hook R and adjustable arm S, and trip *e*, secured on the lower extremity of said spindle, substantially as shown and described.

26. The combination of the arms R S, trip *e*, trip *c*, trigger C', dogs *f*, pivoted at the sides of the standard H, tray D², pin C, attached to the drive-bar D', and wheel N', and 20 means engaging therewith to partly revolve it, substantially as set forth.

27. The catch-lock B', provided with a central opening, a spring, D, and tooth *b'*, in combination with the bar E' and spring-actuated 25 collar J', substantially as set forth.

28. The arm E', arranged as shown and described, in combination with the tooth *b'* on the catch-lock B', and mechanism, as described, for throwing the shaft into connection 30 with the driving-wheel, as set forth and described.

29. The trip *e* on the spindle G, in combination with the trigger C' of the catch-lock B', substantially as set forth and described.

30. The combination of the wheel N', spindle G, with trips *e* *c*, standard H, with pivoted spring-dogs *f*, feed-bar Q, with arms R S, pin C and means for operating the same, pawls *j* *j'*, and trigger C', substantially as described.

31. The combination of the drive-bar D', tray D², and jog-link D³, with pivoted arm A', dogs *u* *v*, vise V, feed-bar Q, provided with arms R S, trip *e*, arranged on spindle G, trip *c*, dogs *f*, wheel N', pawls *j*', catch-lock B', 45 provided with trigger C' and beveled tooth *b'*, arm E', collar J', spring K', and feather I', all arranged and operating as and for the purpose hereinbefore set forth.

32. The wheel Q', with raised periphery *m'*, 50 in combination with the pivoted arm R', auxiliary presser-foot P', and spring O', substantially as and for the purpose set forth.

33. The catch-lock B', with spring D, bearing upon the lower portion, and with the upper part extended through the casing or bed-plate of the machine, in combination with the trip *e* on the spindle G, arm E', sliding collar J', spring K', feather I', and driving-wheel M', substantially as set forth.

In testimony whereof I have hereunto set my hand in the presence of two subscribing witnesses.

FREDERICK EGGE.
